DESIGN FOR A GLOVE

Renaté Riedner, New York, N. Y.

Application October 4, 1938, Serial No. 80,242

Term of patent 14 years

To all whom it may concern:

Be it known that I, Renaté Riedner, a citizen of Germany, and a resident of the city of New York (Borough of Queens), county of Queens, and State of New York, have invented a new, original, and ornamental Design for a Glove, of which the following is a specification, reference being had to the accompanying drawing forming part thereof, in which—

as shown in Fig. 1, with the thumb in the foreground.

The design is characterized by a row of stitching extending down the center of each fourchette in combination with the matching stitching around each finger and continuing down the side of the little finger to the cuff as shown.

I claim:

The ornamental design for a glove, substantially as shown and described.

RENAË RIEDNER.
